Atty.

UNITED STATES PATENT OFFICE.

JAMES McKECHNIE, OF BARROW-IN-FURNESS, ENGLAND, ASSIGNEE TO VICKERS
LIMITED, OF WESTMINSTER, ENGLAND.

FABRIC FOR AIRSHIPS, BALLOONS, &c., AND METHOD OF MANUFACTURING THE SAME.

1,316,456.

Specification of Letters Patent. Patented Sept. 16, 1919.

Application filed May 8, 1917. Serial No. 167,171.

To all whom it may concern:

Be it known that I, JAMES McKECHNIE, a subject of the King of Great Britain, residing at Naval Construction Works, Bar-
row-in-Furness, in the county of Lancaster, England, have invented certain new and useful Improvements in or Relating to Fabric for Airships, Balloons, &c., and Methods of Manufacturing the Same, of which the
10 following is a specification.

This invention relates to the manufacture of fabric employed in the construction of airships, balloons and similar craft of the kind wherein biased or diagonal cut material is used. Heretofore, it has been the practice to connect together several rhomboidal-shaped pieces to form lengths or strips of material having diagonal warp threads and to so arrange the said lengths or strips that in some of them the warp threads have a right hand lay or bias, thus enabling an envelop to be produced in which the lengths or strips alternately possess warp threads of right and left hand bias. The
15 chief object of the present invention is to avoid the use of the small pieces of fabric of rhomboidal shape in making the lengths or strips of biased or diagonal cut material, thereby eliminating the numerous sectional
20 joints and the labor they involve and obtaining a light and more evenly finished envelop than heretofore and one possessing a more uniform elasticity.

According to the invention the fabric or material is woven in any well known manner in the form of a double cloth with the selvage made as nearly as practicable the same as the main portion of the fabric so that when delivered from the loom it is in
25 the form of a tube. This tube is then cut along a line forming a right or left hand helix, thus producing in a manner well understood in the textile art, a long continuous length of biased or diagonal cloth. The helical line may of course be determined by passing the tubular cloth over a cylindrical templet, or (while the cloth is in the double flat condition) by the aid of templets or other appropriate means, which will enable
30 the desired marking and cutting of the cloth to be performed. The long continuous

lengths of the biased or diagonal cloth thus produced are then combined to form an envelop in such a manner that variations in the strength and extension of the threads 55 forming one section or gore piece of the envelop will be equalized or compensated for by corresponding variations in the strength and extensions of the threads forming the adjoining section or gore piece, with 60 the result that the extension of the threads will be practically equal in all directions, thus preventing distortion or deformation of the envelop. In some cases the said continuous lengths of biased cloth may be combined in layers with other long continuous 65 lengths of unbiased cloth *i. e.* cloth woven in the ordinary manner; thus a continuous biased or cross-cut length may be combined with an ordinary straight cut continuous 70 length to produce a two-ply fabric having the warp threads in the alternate sections or gore pieces of the finished envelop running respectively right and left to counter-balance the twisting effect. Any suitable 75 number of long continuous lengths or layers of the biased or diagonal cloth may, however, be used according to requirements, but usually two will be sufficient. For combining or attaching together the long continuous 80 lengths or layers of the cloth, rubber or other adhesive and proofing substances may be employed, or they may be connected in any other suitable manner; thus the airship or balloon fabric made from long continuous 85 lengths as above stated may be proofed with rubber or other proofing.

The woven tubular fabric may be cut to produce the long lengths of biased or diagonal cloth, either by hand actuated means 90 or by passing same through a suitable machine.

In order that the invention may be clearly understood and readily carried into effect the same will now be more fully described 95 with the aid of the accompanying drawings, in which:—

Figure 1 represents diagrammatically a portion of the tubular woven fabric and the direction in which it is cut along a left hand helix.

Fig. 2 is a fragmentary view showing the

warp threads of two lengths of the biased or diagonal cloth combined together in layers.

Fig. 3 is a fragmentary view showing the 5 warp threads of two lengths of the biased or diagonal cloth combined with a length of ordinary woven or unbiased cloth. Only one set of the threads, viz. the warp threads, is indicated in Figs. 2 and 3, it being understood that the other or weft threads will be 10 at right angles to those shown.

Fig. 4 is a fragmentary view showing diagrammatically how the biased lengths are arranged edge to edge with the bias alternately right and left handed.

a (Fig. 1) indicates the tubular fabric and *b* indicates the left hand helical line along which the fabric is cut to produce a continuous length or strip of biased cloth 20 equal in length to the said line *b*.

In the employment of two lengths of the biased cloth, the arrangement indicated diagrammatically by Fig. 2 shows how the warp threads in one length appear relatively 25 to the warp threads of the adjacent length when one length is laid on the other with the warp threads crossing each other at right angles. Fig. 3 shows how the warp threads appear when two lengths of biased cloth are 30 combined with one length of ordinary woven cloth. By making the cloth in long continuous lengths and thus avoiding the necessity of numerous joints, a more even spreading of the rubber or other proofing is attainable 35 without interfering with the doctor knife on the spreading machine. Owing to the absence of the joints, some reduction in the weight of the finished cloth is obtained as well as a saving in labor. When only one 40 length or layer of biased or cross-cut cloth is used alone or combined with a length or layer of ordinary straight cut cloth the twisting effect in the finished balloon or envelop may be prevented or resisted by 45 arranging the alternate length sections or gore pieces so that while one length has a right hand bias the adjoining length or lengths have a left hand bias (see Fig. 4). In this way the varying strength and extension of the threads forming one length or 50 section will be equalized or compensated for by the varying strength and extension of the threads forming the adjoining length or section. As in Figs. 2 and 3 only one set 55 of threads is indicated in each length or section in Fig. 4.

The cutting of the tubular woven fabric may be effected along either a right hand or a left hand helical line to obtain lengths with 60 a right or a left hand bias. If the lengths with a right hand bias are combined in layers with those of a left hand bias the crossing of the threads of one length with another will be at right angles without requiring one length to be reversed relatively 65

to adjacent length as is necessary when lengths of all right hand or all left hand bias are employed.

In lieu of two lengths one length of double width may be folded longitudinally 70 so that the threads cross each other in the required direction, the width of the lengths to be folded being determined by the diameter of the woven tubular cloth. The cloth may be woven either in a circular loom or 75 in a plain loom as may be found expedient.

What I claim and desire to secure by Letters Patent of the United States is:—

1. A method of manufacturing fabric envelops for use in airships, balloons and similar craft, which consists in spirally cutting a tubular cloth to obtain long continuous lengths of biased cloth, combining said continuous lengths so that the threads of one length extend in a different direction to the 80 corresponding threads of the other length and joining the edges of said lengths together to form the envelop, for the purpose specified.

2. A method of manufacturing fabric envelops for use in airships, balloons and similar craft which consists in cutting a tubular woven fabric along a right hand helical line to obtain long continuous lengths of cloth, cutting a tubular woven fabric along a left 90 hand helical line to obtain further long continuous lengths of cloth, arranging said 95 lengths alternately and joining the edges of adjacent lengths together to form the envelop.

3. A method of manufacturing fabric envelops for use in air ships, balloons and similar craft which consists in making long continuous lengths of cloth by cutting tubular woven fabric along right and left hand 100 helical lines, combining said long continuous lengths of cloth in layers with ordinary woven cloth, and joining the edges of adjacent lengths of said combined layers together to form the envelop.

4. A method of manufacturing fabric envelops for use in airships, balloons and similar craft, which consists in cutting a fabric woven in the form of a tubular cloth along a line forming a helix so as to obtain long 115 continuous lengths of biased cloth and combining said continuous lengths edge to edge with the bias alternately right and left handed for the purpose specified.

5. For use in the construction of fabric 120 envelops for airships and similar craft a fabric comprising layers of long continuous lengths of biased cloth cut helically from lengths of tubular woven fabric combined with layers of long continuous lengths of 125 ordinary woven cloth, alternate sections being arranged edge to edge so that while the length in one section has a right hand bias the adjoining length in the adjacent section has a left hand bias.

6. For use in the construction of fabric envelops for airships, balloons and similar craft, a fabric comprising in combination long continuous lengths of diagonal cloth
5 cut helically from lengths of tubular woven fabric with the addition of a layer of other long continuous lengths of ordinary woven cloth, the said lengths lying edge to edge with the bias alternately right and left handed substantially as hereinbefore described 10 for the purpose specified.

In witness whereof, I affix my signature.

JAMES McKECHNIE.
